UNITED STATES PATENT OFFICE.

WILLIAM C. MILLER, OF PITTSBURG, PENNSYLVANIA.

TACK-PULLER.

SPECIFICATION forming part of Letters Patent No. 743,183, dated November 3, 1903.

Application filed July 11, 1903. Serial No. 165,091. (No model.)

To all whom it may concern:

Be it known that I, WILLIAM C. MILLER, a citizen of the United States of America, residing at Pittsburg, in the county of Allegheny and State of Pennsylvania, have invented certain new and useful Improvements in Tack-Pullers, of which the following is a specification, reference being had therein to the accompanying drawings.

10 This invention relates to certain new and useful improvements in tack-pullers; and the primary object of the present invention is to construct a tack-puller with its handle so shaped that when the handle portion of the tack-puller is forced toward the floor during the operation of the pulling of the tack the hand of the operator will be protected in such a manner as to effectually prevent the same coming in quick contact with the floor 20 and being injured thereby.

A further object of the present invention is to construct a tack-puller of extremely simple construction, one that will at the same time be strong and durable and cost 25 comparatively little to manufacture.

With the above and other objects in view the invention consists in the novel construction, as will be hereinafter more specifically described and then particularly pointed out, 30 and in describing the invention in detail reference will be had to the accompanying drawings, forming a part of this application, and wherein like numerals of reference will be employed for the designating of like parts throughout the different views of the drawings, in which—

Figure 1 is a side elevation illustrating the position of the implement after the tack has been pulled out of the floor and showing the 40 manner in which the hand is protected and prevented from contact with the floor. Fig. 2 is a detail top plan view of my improved tack-puller, and Fig. 3 is an underneath plan view of the same.

45 A tack-puller constructed in accordance with my invention is made from a suitable piece of material. As practiced by me I have preferably employed sheet metal, band-metal, or other like material of a suitable thickness, 50 though the implement might be cast or molded. However, I prefer to employ sheet or band metal of a suitable thickness to afford

the desired strength in the implement and cut therefrom a strip of the desired width. This strip of metal I form into the desired 55 shape by means of a former, shaper, or die to produce the foot 1, provided in its end with a substantially V-shaped notch 2, which is adapted to receive the shank of the tack to be pulled. The handle portion 3 of the implement is given a return bend 4, the end of which is on a plane with the heel or fulcrum 5 of the foot member of the implement after the handle member has been depressed whereby to elevate the forward end of the tack 65 puller or implement in order to extract the tack. This is fully illustrated in Fig. 1 of the drawings, and attention is directed to the fact that the fingers which grip the handle lie above the end of the bend on the handle, 70 and consequently the said end comes first into contact with the floor, and the fingers are therefore protected from contact with and injury by engagement with the floor. The shape of the implement enables the operator 75 to obtain a firm grasp thereon, the forefinger lying in the curve or depression at the back of the foot member directly over the fulcrum-point, the other three fingers of the hand gripping the handle, with the thumb lying 80 against the edge of the handle, and the fingers of the hand thereby absolutely protected from injury, since as the handle is forced downward the end of the bend will first engage with the floor, but not until the foot has been 85 elevated at its outer end a sufficient distance to extract the tack. In practice the walls of the notch will be beveled off, as shown, so as to permit easy insertion of the foot under the tack-head, and to this end the upper face of 90 the foot at the forward end will be also beveled or inclined, as best seen in Fig. 1 of the drawings. I have shown the foot member as somewhat contracted back of the head, having the notch therein, by which means the thickness 95 of the head is increased slightly to provide for the beveling and notching of the head and still retain the required strength.

While, as stated, I preferably construct the implement of sheet metal, yet will, if desired, 100 cast or mold the same in the same shape as herein shown and described, and consequently in practice various slight changes may be made in the details of construction without

departing from the general spirit of my invention.

Having fully described my invention, what I claim as new, and desire to secure by Letters 5 Patent, is—

A device of the character described, comprising a tack-puller of a single strip of metal having a foot provided with a beveled notch formed upon one end, said end being bent 10 upwardly to act as a fulcrum when said device is in use, and the other end of said metal strip being given a return bend the end of

said bent portion lying in a plane with the said fulcrum when the tack-puller is depressed, thereby serving as a guard for the 15 finger of the operator, substantially as described.

In testimony whereof I affix my signature in the presence of two witnesses.

WILLIAM C. MILLER.
